UNITED STATES PATENT OFFICE

HELEN B. HEBERT, OF SAN DIEGO, CALIFORNIA

DESIGN FOR A DOLL

Application filed January 15, 1931. Serial No. 38,313. Term of patent 7 years.

To all whom it may concern:

Be it known that I, HELEN B. HEBERT, a citizen of the United States, residing at San Diego, in the county of San Diego and State of California, have invented a new, original, and ornamental Design for a Doll, of which the following is a specification, reference being had to the accompanying drawings forming a part thereof.

Figure 1 is a front elevational view of my new design for a doll; Fig. 2 is an edge view thereof; Fig. 3 is a rear elevational view thereof; and Fig. 4 is an enlarged transverse sectional view thereof taken through 4—4 of Fig. 3.

I claim:

The ornamental design for a doll, substantially as shown.

In testimony whereof, I have hereunto set my hand at San Diego, California, this 10th day of January, 1931.

HELEN B. HEBERT.
